UNITED STATES PATENT OFFICE.

NAPOLEON JAMES AND FRANK RUST, OF ALLEGHENY, PENNSYLVANIA.

SHEET-METAL-WORKING MACHINE.

SPECIFICATION forming part of Letters Patent No. 588,436, dated August 17, 1897.

Application filed February 27, 1896. Serial No. 581,002. (No model.)

To all whom it may concern:

Be it known that we, NAPOLEON JAMES and FRANK RUST, citizens of the United States, residing in Allegheny, county of Allegheny, 5 and State of Pennsylvania, have invented certain new and useful Improvements in Sheet-Metal-Working Machines, of which the following is a specification.

Our invention relates to machines for sheet-metal working; and it consists of the hereinafter-described hydraulic stamping and shearing machine illustrated in the accompanying drawings, wherein—

Figure 1 is an elevation of the machine complete. Fig. 2 is a top view, the main water-tank and tubing above the line 2 2 in Fig. 1 being removed. Fig. 3 is a top view of the operating parts from line 3 3 in Fig. 1 downward. Fig. 4 is an enlarged detail, a 10 plan of the mold, the upper plate having been removed to show the trimming-cutters. Fig. 5 is an enlarged vertical section showing the cutter in its setting. Fig. 6 is a vertical longitudinal section of the mold. Fig. 7 is a vertical longitudinal section of the die, and Fig. 25 15 8 is a top view of it. Fig. 9 is an enlarged detail, a vertical section showing the rim-cutter in operation. Fig. 10 is a similar view of the cutter receded. Fig. 11 is the plan of the 30 roughly-cut blank of sheet of metal from which a bath-tub is to be pressed.

Similar letters of reference indicate corresponding parts in all views.

Our improved stamping and shearing machine is constructed with the view of employing the weight of water in an elevated tank for operating the die pressing a sheet of metal into the mold. The water in the tank is controlled by valves operated by steam or other 35 motive power. The water stored in tank A, elevated to a high level, is conducted therefrom by six or more tubes *a* into the receiving-tank B. The outlet-tubes *a* of tank A are controlled by spherical valves *v*, suspended from levers *l* and *la* and fulcrumed 40 to the tank A. Valves *v* are connected by rods *ber* to the operating mechanism and controlled from below. Receiving-tank B is suspended below the tubes *a* by wire ropes (or 45 chains) *c*, passing over pulleys *p*, pillowod on frame F, and is balanced by counterweights W, so that when there is no water in the tank

B the weights W will lift it to its highest position. The bottom of the tank is conically shaped, sloping toward its center, and in the 55 center thereof is secured to it base-plate B', to which strut-rod *s* is secured by bolts *xv*.

The stamping-die is operated by alternately filling tank B with water from the upper tank A and by emptying it again. Tank B falls 60 when water is admitted into it and forces the die down with the full weight of the water. When the operation of the die is performed, the water is exhausted from this lower tank B through the two tubes *b*, set in its bottom 65 and sliding vertically and concurrently with the motion of tank B in the stationary tubes *bb*, and there is no break in the exhaust-tubes in any position of the tank. Valves *vb*, controlling these exhaust-tubes, are also spherical 70 and suspended on chains *cv* from levers *lv*, pivoted to the frame F, and these levers *lv* are also connected to the operating mechanism and controlled from below. Valves *vb* can only be open when the tank B is at its 75 lowest position, for when it is raised chains *cv* will be slack and the valves will sit in their seats, closing the tubes *b*.

Rollers R, pillowod in brackets *rb*, secured to the sides of the tank B, guide the motion 80 of the tank along guide-rails T, secured to the sides of vertical posts F of the frame. This frame consists of the vertical posts F, set in substantial foundations and bound together by brace-beams near their tops. Their 85 tops, extending above the brace-beams *f*, carry the bearings of pulleys *p*, carrying wire ropes *c*, sustaining and moving the tank.

To the base-plate B', provided in the center of the conically-shaped bottom of the tank 90 B, is secured the strut-rod *s* by screw-bolts *xv*, and to the other end of this rod is secured the die D, shaped in accordance with the article to be pressed. The lower end of the rod *s* is formed with a square flange *sf*, which 95 engages under the collar *dc*, secured to the die D by bolts.

The stamping mold and block consists of the lower die M proper, supported on legs L, embedded in the foundations of the machine. 100 The mold in the die is larger than the largest desired size of the article to be pressed, and is changeable through insertion of linings E to vary the size of the article produced with-

out necessitating a change of the mold-casting. The lining should also be changed when the sheet metal from which the article is pressed is changed in thickness. The bottom *m* of the mold *M* is detached from the main casting and rests on the shoulder *ms* in the casting. The lining *em* of the bottom *m* is not attached to the lining *E* of the sides, but is secured to the bottom and moves vertically with it. The top of the casting *M* is extended, so as to form a table on which the sheet of metal is placed before it is pressed. To the under side of the casting *M* are secured the pulleys *ep mp*, over which the cords *pass*, having at their outer ends the counter-weights *w* and being attached at their other ends to the plate *q*, secured to the movable bottom *m* by the rods *n*. This plate is provided with rollers *r*, bearing against the inner edges of the legs *L* of the casting *M* and guiding the bottom in its vertical movement. The bottom *m* is therefore in its most elevated position when there is no weight on the die. Thus when the die descends it will grip the sheet metal between it and the bottom *m* and will keep it from being forced out of its central and correct position as it descends, and then when the die rises again the weights *w* will lift the bottom *m* and force the finished article from the mold.

When it is desired to provide the tub with a flat rim on which to screw a wooden face, we trim the edge of the sheet metal by a vertical knife, which cuts the edge of the rim smoothly and evenly. The cutting-knife *K* slides vertically in slot *d* in the lower side of the die *D* and is actuated by the rods *o*, secured to it at intervals along its length. These rods *o* pass vertically through the die *D* and are provided at their upper ends with the pins *ol*, engaging the slot in the end of the lever *dl*. The knife is kept in its upper position by the spiral spring *sp*, coiled around the end of the rod *o* and bearing against the lever *dl*, lifting it and the knife *K*. This lever *dl* is pivoted in the bracket *db*, secured on top of the die *D*. The other end of the lever *dl* is provided with a slot *st*, in which the pin *pl*, attached to the rod *ro*, engages. Rod *ro* moves vertically in the bracket *br*, secured to the side of the die, and is of such a length that when the knife is in its raised position rod *ro* projects below the edge of the die *D* and will when the die descends strike the mold *M* and slide up the side of the die, thus forcing the knife *K* downward to cut the material beneath it. If, however, it is desired to provide the bath-tub with a curved edge, we use the curved lining and die, and then trim the edge thus bent downward by a horizontally-reciprocating knife. In this case the top of mold *m* is cut lower, and on the upper surface of *M* slide knives *h lk km kn*, one on each side of the mold, and they join in their forward or cutting motion after having passed about one-sixteenth of an inch beyond the rim. Tongues *mt*, fitting in the slots *ks* in

the knives *k*, &c., project in the plane of the cutters and guide them to make a clean and uniform cut.

Above the knives *k*, &c., is screwed the keeper-plate *kp* to the mold *M*, holding them in position, and for removing of the knives for sharpening or other purposes it is only necessary to unscrew the keeper-plate *kp* and then lift the knives from the mold.

The cutting-dies are actuated by levers *sl*, secured to and rotating with the shafts *S Sa Sb Sc*. These levers *sl* enter into holes *kh* of the cutting-dies and force the knives forward to cut the rim of the sheet, separating the part below the die. Shafts *S Sa Sb Sc* lie in the slots *Ss* in the mold and are journaled in bearings *Sj* in these slots. The shaft *S*, actuating the knife *k*, is rotated by the lever *le* on its end and is provided with the beveled cog-wheels *ca cb* or segments thereof, gearing with the beveled wheels *cc cd*, respectively. The wheel *cc*, gearing with *ca*, is secured to the shaft *Sa* and actuates the knife *kl*. The wheel *cd*, gearing with *cb*, is secured to the shaft *Sb* and actuates the knife *km*, while at the other end of this shaft *Sb* is secured the beveled segment *ce*. This segment *ce* gears with the segment *cf*, secured to the shaft *Sc*, and actuates the knife *kn*. Thus all the knives are moved by the lever *le*, which is forced with great power by the wipers *es fs*, secured to piston-rod *er* of the steam-cylinder *Ce*, controlling the exhaust-valves *vb* of the tank *B*.

On the foundations, beside the mold *M*, are placed the two cylinders *Ca Ce* back to back and each connected by pipes to the steam-valve *Va*. This valve *Va* is circular and is controlled by hand. It is provided with a right-angled port leading through the plug. The steam admission and exhaust pipes *Bp Ep* enter, respectively, at the top and bottom of the valve-case *Vc*, and the two cylinder-pipes *pc pd* are connected thereto at right angles to said steam admission and exhaust pipes. Thus by turning the cock *Va* into proper position either cylinder may be placed in connection with the boiler-pipe *Bp* or with the exhaust-pipe *Ep*.

The cylinder *Ca* is provided, as usual, with a piston-rod *Ra*. This piston-rod is provided with a pin at its end engaging in a slot in the bell-crank lever *bcl*, pivoted to a standard secured in the foundations, and the other end of the bell-crank lever *bcl* is connected to the lever *l* by the rod *bcr*.

Bracket *Rb* is secured to one side of the piston-rod *Ra*, and to it is attached the rod *Rr*, running parallel with the piston-rod, but in the opposite direction. This rod is attached to another bell-crank lever *bcr*, similarly mounted, and operates the lever *la*. Thus the levers *l la*, with the six valves hung therefrom, are actuated by the steam-cylinder *Ca*. Cylinder *Ce* is slightly longer than cylinder *Ca* in order to win the necessary length of stroke to actuate the knives *k*. Piston-rod *er* of this

cylinder operates the two bell-crank levers *bca* *bco*, and these are connected to the above-described levers *lv* by the rods *bcs* *bct*. Thus the exhaust-valves *vb*, suspended from the levers *lv*, are operated by the cylinder *Ce*. To the side of the rod *er* are also secured the two wipers *es* *fs*, which actuate the lever *le*, controlling the knives *k*, &c., as described.

The operation of our machine is as follows:

10 Tank B when empty is in its normal elevated position and the die D above the mold M. On the table of the mold sheet of metal SM, previously cut to the required size, is placed on the table of the mold. When the valve *Va* is turned to admit steam in the cylinder *Ca*, the six valves *v* are lifted and admit water into the tank B from the tank A. Then tank B descends, pressing the die D down on the sheet metal SM. This is kept in its place by the pressure of the die and by the movable bottom *m* on each side of it. Then as the die descends farther the sheet metal is pressed into the mold M and drawn and pressed into the desired form. Then the steam 25 is exhausted from the cylinder *Ca* and the weight of the parts closes the admission-valves *v*. The press is allowed to remain in this position until the sheet of metal is set. Then the steam is admitted into the cylinder *Ce*, forcing the trimming-knives forward and at the same time opening the exhaust-valves *vb*. The water flows then into a subterranean tank, whence it is lifted again by pressure-pumps into tank A. Tank B when emptied 30 rises and draws die D from the mold, and at the same time the weights *w* force the movable bottom *m* upward and lift thereby the finished article from the mold. The steam is then exhausted from the cylinder *Ce* and the 35 machine is ready for another operation.

We claim and desire to secure by Letters Patent—

1. The hydraulic apparatus for operating a stamping and shearing machine, comprising a stationary storage-tank for water, a sliding tank, having a conical bottom, suspended underneath the storage-tank, a base-plate secured to the center of this conical bottom, a flanged truss-rod secured to the base-plate, and adapted to carry the pressing-die on its lower end; outlet-tubes, set in the bottom of the stationary storage-tank, valves closing the inlets of these tubes; outlet-tubes set in the bottom of the sliding tank and sliding in stationary outlet-tubes, valves closing the outlets of the telescopic tubes in the bottom of the sliding tank, levers fulcrumed in standards, secured to the walls of the storage-tank, and connected by chains to the valves; connecting-rods and bell-crank levers, operating

the levers, and connecting-rods operating the bell-crank levers by the motion of the piston of the engine.

2. In a hydraulic stamping and shearing machine, comprising a stationary storage-tank, and a sliding tank movably suspended underneath, outlet-tubes set in the bottom of the storage-tank; outlet-tubes, set in the bottom of the sliding tank, valves closing the outlet-tubes; the combination with levers and connecting-rods for operating the valves, of a steam-engine comprising two combined working cylinders, one of them operating the outlet-valves of the stationary storage-tank and the other, the outlet-valves of the sliding tank, 65 both cylinders being connected to a common steam-inlet and to a common exhaust-pipe, having a two-way cock set in the cross connection of the pipes, and adapted to connect alternately and successively either of the two cylinders with the inlet and with the exhaust pipe, for the purpose of operating alternately and in successive order the valves of the tanks and thereby lifting and lowering the sliding tank, operating the die. 70

3. In a shearing and stamping machine, the combination with the upper die, of cutters sliding in the grooves provided in the upper die parallel with its edges and in conformity with the shape of the sheet to be cut, and of levers fulcrumed in standards, attached to the die, and of push-rods, connected to the levers, and operating the knives by pushing the levers upward, when the upper die descends on the mold and their motion is arrested by the rim of the mold. 80

4. In a shearing and stamping machine, the combination with the mold of cutters, shaped in conformity with the shape of the rim of the product and adapted to slide on the surface of the mold; and of shafts, pillow'd in the mold, of cams set on the shafts and entering into recesses provided in the knives, of levers secured to the ends of the shafts, wipers, secured to the connecting-rod of the engine and adapted to engage the levers secured on the ends of the shafts, and by moving them, turn the shafts and thereby to operate the cutters, trimming the edges of the rim of the product pressed in shape by the action of the die. 90

In witness that we claim the improvements described in the foregoing specification we have signed our names in the presence of two subscribing witnesses.
